Application August 7, 1939, Serial No. 288,752

2 Claims. (Cl. 173—328)

This invention relates to sockets more particularly such as are used in radio apparatus for holding electronic tubes having prong terminals. Such sockets are used also as receptacles for cable terminal plugs where the plug is provided with prongs for making electrical connection with the contact members of the socket.

Among other objects, the invention aims to provide an improved socket of this type which may be produced and assembled in large quantities at low cost and which at the same time has enhanced mechanical and electrical efficiency, particularly for tubes or plugs in which one of the prongs is in the form of a relatively large center pilot pin provided with rotative position fixing means and also itself affording an electrical contact, while the other prongs or electrodes are of relatively small diameter and as many as say eight in number, the whole being encompassed within a relatively small circular area approximately three-eighths inch radius.

Other objects and advantages will be apparent from the following description, taken together with the accompanying drawing, in which—

Figure 1 is an elevational view of a socket constructed in accordance with the present invention and associated with a radio chassis panel and radio tube, the latter being shown in separated relation, and the chassis portion being in section, the parts being approximately actual size;

Figure 2 is an enlarged plan view of the socket alone with parts broken away and in section for clearness of description and also with one of the contact members sectioned through its tail; also with another of the contact members shown as it would be spread by the action of a tube prong received therein;

Figure 3 is a vertical section taken on the staggered line 3—3 of Fig. 2 through the spread contact;

Figure 4 is a bottom view of the structure of Fig. 2 and again showing a fragment of the chassis associated therewith;

Figure 5 is a separated view of the center contact shown in previously mentioned figures;

Figure 6 is a development view of the structure of Fig. 5;

Figure 7 is a separated view of one of the other contacts shown in previously mentioned views; and

Figure 8 is a plan view of an illustrative retainer spring as shown in section in Fig. 1.

Referring in detail to the illustrative construction shown in the drawing, the radio chas-

sis 10 may have a generally circular opening 11 therein to snugly receive the socket 12. As here shown, the socket 12 comprises an insulating body 13 desirably formed of molded insulating material such, for example, as a phenolic condensation product commonly known as "Bakelite." The body 13 carries the metal socket or contact members specifically, one of which 14 at the center of the body makes contact with the center prong 15 of the conventional electronic tube 18, and the others of which 16, eight in number in this instance, make contact with the corresponding eight prongs 17 of the tube.

The cylindrical molded body 13 while somewhat 15 disk-like, is desirably of materially great thickness with respect to its diameter, and as here shown has a peripheral shoulder 19 which rests upon the upper face of the metal chassis 10, the cylindrical lower end 20 of the body 13 below the shoulder 19 passing snugly downwardly through the opening 11 in the chassis. The body lower end 20 has a peripheral groove 21 in which may be seated the retaining spring 22 which locks the body to the chassis, as best shown in Fig. 1. 20 One form of such retaining spring 22 is shown in Fig. 8 of triangular shape in which the corners 23 are resiliently disposed in a plane normally offset from the plane of the intermediate parts 24 of the spring 22 thus providing the desired tension after the socket has been placed in position on the chassis.

As best shown in Fig. 4, the socket lower end 20 also has a plurality, in this instance, four peripheral notches 25 in one of which may be received the locating projection 26 of the chassis 10 which extends into the opening 11. These notches permit selective rotative positioning of the socket in the chassis with the projection 26 in any one of the notches 25 and thereafter preventing relative rotation of the socket with respect to the chassis.

It will be understood that the present invention is not directed to the mounting of the socket just described, this being for purposes of exemplification, and that other mounting means may be employed, such for instance as an adaptor plate secured to the socket body and which may be riveted to the chassis as is well known in the art and need not be here specifically described.

Turning now to the interior construction of the socket 12 which is the subject of the present invention, the parts within the area defined by the circle 27 will be described.

The area defined by the circle 27 is relatively small, approximately seven-eighths inch in di-

ameter, and is spaced approximately three-sixteenths of an inch inwardly from the over-all diameter of the socket. This area contains a plurality, in this instance eight axial passages arranged as a group on the line of an annulus around the center of the socket and uniformly spaced apart therefrom and one from the other. Each of these axial passages includes an enlarged trough-like and desirably wedge-shape upper end 28 which opens into a counterbore 29 in the upper end of the body 13. This counterbore 29 is offset radially inwardly of a cylindrical recess in the upper end of the socket defined by the circle 27 and providing a shoulder 27a which extends annularly in segments separated by radial ribs 27b which are upper projections of the walls of the separate axial passages 28. As here shown, the wedge-shape passage part 28 tapers decreasingly downwardly to a slot 30 which opens through the lower face 31 of the body.

In each of these axial passages is located one of the metallic contact members 16, which as best shown in Fig. 7, comprises a tail 32 and a resilient prong engaging part 33. Each of the contact members 16 is advantageously a one-piece metal stamping having spring temper. When the contact member 16 is assembled with the body part 13 it is put in from the upper end of the body and the contact tail 32 passes downwardly through the slot 30 to project from the body lower end, the tail 32 having the soldering hole 34 therein to which a conductor wire may be attached, or the wire may be wrapped around the intermediately reduced part 35 of the tail 32. Downward movement of the contact member in the body is limited by the intermediately obliquely bent portion 36 of the contact which prevents passage of this part through the slot 30.

Above the bent part 36, the contact member 16 is extended upwardly as at 37 parallel with but offset from the tail 32 and is again obliquely bent at 38 and then continued upwardly as at 39 in a part parallel with the parts 32 and 37 but still further offset from the tail 32. At its uppermost end the contact 16 is turned horizontally or at a right angle to the passage as at 40 to form the prong engaging portion proper. When the contact member is inserted downwardly as somewhat yieldingly limited by the bent part 36, the bent part 38 rests against the tapered wall of the opening portion 28 as at 41 and the free end 42 of the prong engaging part 40 of the contact advantageously rests as at 43 upon the shoulder 27a occurring between the recess defined by the circle 27 and the counterbore 29. Thus the prong engaging part proper 40 of the contact member is cushioned for purposes next described.

In the horizontal prong engaging part 40 of the contact member is a perforation 44 through which is received one of the prongs 17 of the tube. As here shown, the entire prong engaging part 33 of the contact member is advantageously split from its free end as at 45 on a line passing through the center of the perforation 44 and extending downwardly to the part 31. The perforation 44 is desirably made by piercing the metal of the horizontal part 40 and drawing it downwardly as best shown at 46 (Fig. 3) to an extent preferably greater than the thickness of the metal itself, thus affording an enhanced contact surface with the prong. Thus advantageously no metal is removed from the prong engaging part of the contact member and its split portions are normally in contact substantially throughout until receipt of the prong.

The perforation 44 is normally of less diameter than the prong 17, and the split 45 permits the prong to be received in the perforation 44 with a scraping resilient engagement which not only improves the electrical conductivity therebetween but also is a factor in permitting the contact to accommodate itself to the prong. This is further enhanced by the somewhat floating character of the prong engaging part 33 of the contact member in the trough-like passage part 28. A characteristic of the invention is the controlled resilience of the contacts provided by the structure described which not only prevents breakage of the seal of the tube about the prongs which might otherwise occur due to bending or wedging strain on the prongs, but also prevents distortion of the prong engaging part of the contact member beyond its elastic limit.

When the contact members 16 have all been inserted as already described in the body 13, they are retained in position against upward displacement, in the present embodiment of the invention, by an insulating disk 47 also desirably of a phenolic condensation product or the like, which fits snugly in the recess defined by the circle 27 and has openings 48 therethrough registering with the perforations 44 in the contact members respectively, the disk 47 resting upon the ribs 27b and center core 41a, the upper surfaces of which are co-planar, and also substantially flush with the contact member portions 40 upper surface.

In this instance the disk 47 is retained in position flush with the upper surface of the socket as shown and described by a preformed shoulder 49 on the upper end of the central grommet-like contact member 14 which passes downwardly through a central opening 51 in the disk 47 and a corresponding central axial passage 52 in the socket body 13. Another shoulder, as presently described, is then formed at the lower end of the contact member 14 to complete its grommet-like character and to secure the parts in position.

As shown in the development view, Fig. 6, of this central contact member 14, it has an initially flat form as at 50 having a somewhat rectangular part 53 forming the head of a T-shape figure of which the leg is the part 54 and on each side of which are the tabs 55 depending from the head 53. When, now, the part 53 is bent around upon itself as shown in Fig. 5 it assumes the somewhat cylindrical form of the central contact 14 having the two free wings 56, the free ends 57 of which are turned outwardly. When the wings 56 are compressed to insert the central contact 14 in the openings 51 and 52 in the disk and body, the free ends 57 of the contact are resiliently received in an axial keyway 58 formed jointly in the disk 47 and body 13. Thus the disk 47 and body 13 are held against both axial and rotative relative displacement. Part 54 of the contact member 14 forms a soldering tail similar to the tails 32 of the contact members 16. It may have the soldering hole 59 therein and be off-set as at 60 to place this part nearer the axis of the socket and away from the other contact members.

The lower edge 61 of the blank 50 for the contact 14 may be slightly sheared to form partly separated edge portions 62 which may be bent as at 63 to lock the contact in position, and also to complete the grommet-like character of the contact to clamp the socket parts together.

When the tube 18 is inserted in the socket with the relatively large central prong 16 of the tube

passing into the hollow interior of the central contact 14, the radially and longitudinally extending key 64 on the central prong 15 of the tube is received in the axial keyway 58 of the socket, the prong 15 thus acting as a pilot pin by predetermined the relative rotative relationship of the tube to the socket and determining the particular contact 16 with which each particular tube prong 17 will engage for circuit continuing purposes.

Since, as will be already understood, it is intended that an electrical as well as mechanical connection be established between the central prong 15 of the tube and the central contact 14 of the socket, for electrical grounding or other circuit continuing purposes, the resilient sliding contact of the prong key 64 with the resilient wing ends 57 of the contact provides a good electrical connection, and this is further enhanced by inwardly directed segmental bulges formed in the contact tab portions 55 which act as spring fingers 65. These spring fingers 65 are yieldingly received in the annular groove 66 near the end of the tube prong 15 with a somewhat snap-button effect, which also prevents accidental displacement of the tube upwardly of the socket. These spring fingers 65 are desirably continued each for a substantial distance segmentally on opposite sides of the central contact 14.

The main portion of the central contact 14, in addition to its other functions, desirably serves as a shield to prevent intercoupling of current between one contact with its associated prong and another contact with its associated prong.

If desired, additional insulating barriers may be located between the contact passages in the socket, for example, such as the ribs 67 on the lower face 31 of the socket, which lengthen the insulating path for resisting the passage of surface electrical currents. Furthermore, these ribs or projections 67 desirably form pockets which prevent resin or soldering flux from flowing from one contact to another during the soldering operation.

While the tails of the contact members may normally protrude at right angles to the lower surface of the socket as shown in full lines in Fig. 1, they may if desired be fanned out by bending them at an angle other than ninety degrees, as shown in dotted lines in Fig. 1, or, as shown in dotted lines in Fig. 4, the contact tails may be twisted out of their normal plane to create a retaining shoulder at the lower face of the socket, thus further securing the contact members against upward displacement and effecting enhanced electrical insulation between contacts by increasing the distance therebetween.

The preformed shoulder or flange 49 at the up-

per end of the central contact member 14 is desirably received in a depression 68 in the disk 47 so as to be flush therewith.

The rim of the lower part 31 of the socket may be extended axially as at 69 to approximately the same extent as the rib-like projections 67 for, among other things, enhanced electrical insulation.

The insulating body 13 and keeper disk 47 may be further interlocked against relative rotation as at 70.

So constructed and arranged, the contacts 16 adapt themselves to the prongs 17 of the tube within all required limits while preventing undue distortion of the prong engaging parts of the contacts; in other words, controlled resilience is afforded by the construction illustrated, including the pocketing of the upper portions of the contacts between the radial ribs 27b and other parts described.

Having described my invention, I claim—

1. In a socket of the class described, a molded insulating body having a downwardly decreasingly tapered passage therein, said passage being wedge-shape in vertical cross-section at its upper end and terminating in a slot at its lower end, a one-piece sheet metal contact member in said passage having a tail passing through said slot and a flat portion at its upper end transverse to said tail, said contact member being bent obliquely between said tail and said upper flat portion to conform somewhat to the taper of the passage, a perforation in said flat portion, and means for retaining said contact member from accidental removal from said passage.

2. In a socket of the class described, a molded insulating body having a passage therein of downwardly decreasing cross-section, said passage terminating in a slot at its lower end, a one-piece sheet metal contact member in said passage having a tail passing through said slot and a flat portion at its upper end transverse to said tail, a shoulder in said passage, said contact member having a free edge at its upper end resting on said shoulder and being bent between said tail and said upper flat portion to conform somewhat to the decreasing cross-section of the passage, said upper flat portion being split from its free edge medially through the upper flat portion and said split extending downwardly for a substantial distance of its bent portion, said last mentioned portion being itself bent intermediately whereby to contact the wall of said passage at vertically spaced apart points and to be free of said wall therebetween, and means for retaining said contact member from accidental removal from said passage.

ARTHUR J. SCHMITT.
